Patented Jan. 3, 1922.

UNITED STATES PATENT OFFICE.

HENRY O. HANNA, OF OAKLAND, CALIFORNIA, ASSIGNOR OF ONE-HALF TO EDWIN S. READER, OF OAKLAND, CALIFORNIA.

COMBINED CAMP STORAGE BOX AND TABLE.

1,402,290.

Specification of Letters Patent.

Patented Jan. 3, 1922.

Application filed July 15, 1920. Serial No. 396,466.

To all whom it may concern:

Be it known that I, HENRY O. HANNA, a citizen of the United States, residing at 1229 Castro Street, Oakland, in the county of Alameda, State of California, have invented new and useful Combined Camp Storage Boxes and Tables, of which the following is a specification in such full and clear terms as will enable those skilled in the art to construct and use the same.

This invention relates to a combined camp storage box and table and its object is to provide means whereby the materials for camping or picnicking purposes may be stored and carried and two of which boxes may be assembled together and used as a table for camp or picnic purposes.

It will be understood by those familiar with automobiles that there are on almost all machines steps somewhat lower than the floor of the car body. It is customary to place boxes of some kind upon these steps and in the present instance a box is provided for each step, each of which boxes is provided with a cover which may be opened to provide a table when the boxes are removed from the machine and assembled in a suitable holder.

In the present instance the two boxes are placed so that their covers will open in opposite directions and the holder is provided with means to securely hold the two boxes together at the proper height for the box lids to be used as a table.

The legs for supporting the boxes are also provided with means for securely holding the two boxes together and for holding the two box lids horizontally. These legs are also so arranged as to fold into a small compass when not in use.

Another object of the invention is to provide means whereby the two boxes may be securely fastened to the running board of the car.

Other objects of the invention will appear as the description proceeds.

An embodiment of the invention is shown in the accompanying drawings in which the same reference numeral is applied to the same portion throughout, but I am aware that there may be modifications thereof.

Figure 1 is a perspective view of the two boxes as they appear when assembled for use as a table.

Fig. 2 is a side elevation of the two boxes as they appear when assembled for use as a table.

Fig. 3 is a vertical section on the line 3—3 Fig. 2.

Fig. 4 is a plan view of the two boxes assembled for use as a table.

The numerals 1 and 2 indicate the two boxes which are rectangular in form and of a suitable height and width and length to fit on the ordinary automobile steps. These boxes may be provided with suitable partitions, in the present instance indicated by 3 to 8 inclusive. Which partitions divide the box into suitable compartments to prevent the materials placed therein from being broken or jammed in one end of the box.

Each box is provided with a cover as indicated at 9 and 10, said covers having suitable hinges 11 to 14 inclusive for connecting them with the boxes. The covers are also provided with suitable locks 15 and 16 for holding the covers closed.

Each box is provided with four cleats 17 to 20 inclusive, which cleats form guide ways adjacent the ends of the boxes for the upper ends of the legs 21 to 24 inclusive. The legs are connected together by means of horizontal bars 25 and 26. Each of which is slotted as indicated at 27 and 28 to afford means for the adjustment of the legs and to afford means whereby the legs may be folded together for transportation.

Bolts 29 and 30 having suitable wing nuts connected to cross bars and legs, and afford the fulcrum for binding the two boxes together. The legs 22 and 24 each having a brace as indicated at 32 and 33, slightly longer than the width of the boxes for spreading the legs at the bottom and tightly drawing the two boxes together.

The braces may have notches at their ends as indicated at 35 to prevent dislodging them laterally from the legs 21 and 23.

In order to secure the boxes in place on the running board, each running board is provided with a holder to receive bolts 36 and 37, which bolts have suitable wing nuts applied to them when the boxes are placed on the running board to prevent them from being thrown off, as the machine travels over rough roads.

It will be observed that when the boxes are in use as a table, that each box lid 9 and

10 rests upon the top of two of the legs, said legs affording the means to prevent the box lid from turning below the horizontal position when the table is in use.

5 What I claim is as follows, but various modifications may be made in the construction shown in the drawings and above particularly described form, within the purview of my invention.

10 1. A combined storage box and table comprising a pair of storage boxes having lids, legs for supporting and binding the two boxes together at a suitable distance from the floor level, said legs affording means for 15 supporting the box lids when the lids are open.

2. A combined storage box and table comprising a pair of lidded boxes having guides on one side, legs adapted to fit the guides and 20 means to bind the legs and two boxes to-

gether to afford means for supporting the box lids horizontally when they are open.

3. A combined storage box and table comprising a pair of boxes having guides on one side of each box, a pair of legs adapted to fit 25 the guides of each box, the upper ends of the legs forming means to support the box lids horizontally when the lids are open and means to bind the legs against the two boxes to hold said boxes together.

4. A combined storage box and table comprising a pair of storage boxes having hinged lids, legs for supporting and binding the two boxes together at a suitable distance from the floor level and a brace for supporting 25 the legs to hold the two boxes together.

In testimony whereof I have hereunto set my hand this 29th day of May A. D. 1920.

HENRY O. HANNA.
